CLAIM

The ornamental design for a cart, as shown and described.

DESCRIPTION

FIG. 1 shows a perspective view of the cart showing our new design;

FIG. 2 is a front view thereof;

FIG. 3 is a front view thereof;

FIG. 4 is a top view thereof;

FIG. 5 is a bottom view thereof;

FIG. 6 is a left side view thereof; and,

FIG. 7 is a right side view thereof.

The design of FIGS. 1-7 is embodied in a cart that may be used to facilitate transport of a variety of items.
